UNITED STATES PATENT OFFICE.

JAMES WILLIAM CLEGG, OF OLDHAM, ENGLAND.

COMBING MACHINE.

1,418,908.

Specification of Letters Patent. Patented June 6, 1922.

Application filed February 12, 1920. Serial No. 358,289.

(GRANTED UNDER THE PROVISIONS OF THE ACT OF MARCH 3, 1921, 41 STAT. L., 1313.)

To all whom it may concern:

Be it known that I, JAMES WILLIAM CLEGG, a subject of the King of Great Britain, residing at Soho Iron Works, Oldham, in the 5 county of Lancaster, England, have invented new and useful Improvements in and Relating to Combing Machines (for which he has obtained Letters Patent of Great Britain, 105,035, application filed October 14, 10 1916), of which the following is a specification.

My invention relates to improvements in and relating to combing machines which have attached a pneumatic appliance such as 15 the aspirator described in the specification to Roth's British Patent No. 5124 of 1907 (U. S. Patent No. 905,233) for removing the waste from the combing cylinder brushes.

In such machines I have found that there 20 is a tendency for the internal stationary roller or slotted tube which is in communication with the exhaust fan or aspirator to become choked or clogged with accumulated waste sucked by the draught of air through 25 the perforations of the outer rotating tube or screen and to the slot in the inner stationary tube.

Hitherto it has been difficult to clear out and remove this obstruction, and my improvements consist essentially in the provision 30 of means for enabling the inner stationary roller or slotted tube to be cleaned out and the accumulated waste removed readily and quickly.

35 I will describe an embodiment of my invention with reference to the accompanying two sheets of drawings in which:—

Fig. 1 is a back elevation, partly sectional, and Fig. 2 an end sectional elevation of part 40 of a combing machine fitted with an aspirator to which my improvements are shown applied.

In these views—*a* designates the pipe or trunk in communication with the fan or 45 aspirator; *b* the usual stand or frame; *c* the inner stationary roller or slotted tube; *d* the outer rotating perforated tube or screen; *e* and *e'* the gears and *e*² the sprocket wheel by 50 which the tube *d* is rotated by a chain, not shown, from the lap roller; *f* the brush casting and *g* the brush which clears the waste from the needles on the combing cylinder *h* and *i* the detaching roller.

The drawing shows the aspirator trunk 55 connected to two cleaning or waste removing

heads so that the tubes *c* *d*, gears *e* *e'*, sprockets *e*² and remaining parts *f* *g* *h* and *i* are in duplicate.

All the foregoing parts are of the usual construction and operate in the known manner well understood.

For the purposes of my invention I support each inner roller or slotted tube *c* concentrically within its outer tube *d* and dispense with the usual shaft running longitudinally from end to end of the two inner tubes *c*.

In the embodiment illustrated I show the inner tubes *c* supported at their outer ends by rings *j* carried in bearing brackets *j'* having feet *j'* adjustably connected by bolts *k* to slotted bracket *l*. The inner ends of the tubes *c* are connected by rings *m* each with a cross arm and boss *m'* to the ends of a short shaft *n* carried in a central boss or bearing *p* supported adjustably on the frame. Consequently by adjusting the bearing brackets *j'* with the rings *j* and the central bearing *p* the inner tubes *c* can be set and maintained in true alignment. At its outer end each inner tube *c* is provided with a detachable cover *q* having an inspection lid *q'* through which the interior of the tube *c* can be inspected from time to time and when required the covers *q* or either of them can be taken off and the interior of the tubes cleaned out and accumulated waste removed readily and quickly.

What I claim as my invention and desire to secure by Letters Patent of the United States is:—

1. In a combing machine, the combination of an inner stationary tube and an outer rotatable tube, and an aspirator in communication with said tubes at one end thereof, the outer end of said inner tube extending beyond the outer tube and provided with a detachable cover.

2. In a combing machine, the combination of an inner stationary tube and an outer rotatable tube, the inner tube extending at one end beyond the outer tube and supported independently thereof, the supporting means for the inner tube being adjustable radially of the outer tube.

In testimony whereof I have signed my name to this specification.

JAMES WILLIAM CLEGG.

Witness:

S. W. GILLETT.
